LOCKING THREAD CARRIER BAR

Franz Cecka, Chemnitz, Germany, assignor to
Schubert & Salzer Maschinenfabrik Aktien-
gesellschaft, Chemnitz, Germany

Application November 29, 1940, Serial No. 367,837
In Germany December 5, 1939

8 Claims. (Cl. 66—127)

The present invention relates to a device for locking the thread carrier bars of flat knitting machines.

With the hitherto used devices for locking the thread carrier bars of flat knitting machines all thread carrier bars are locked in the moment they strike against stops limiting their stroke, whereupon on movement in the opposite direction all the thread carrier bars are unlocked again, so that the inoperative thread carrier bars may be displaced under the influence of vibrations of the machine.

To prevent this drawback an electromagnetic control mechanism for the locking devices of the thread carrier bars has been proposed by which some of the locking devices only are actuated in such a manner that the operative bars are released only in the moment of their departure.

Moreover, to obviate the disadvantage mentioned above a purely mechanical solution also has been proposed which prevents the drawback occurring in connection with electric control mechanisms.

Both solutions, however, require, for effecting the control of the corresponding commands, so-called pattern devices which in a manner known per se may consist of drums, chains, cards, or the like.

The devices according to the present invention are characterized by the fact that locking levers acting upon the thread carrier bars are directly influenced by the change device of the thread carrier bars without requiring special pattern mechanisms.

In the accompanying drawings one construction according to the invention is shown by way of example.

In these drawings:

Fig. 1 is a side elevation of a device according to the invention,

Fig. 2 shows a rear view of the device according to Fig. 1,

Fig. 3 is a rear view looking in the direction of the arrow A of Fig. 1, and

Fig. 4 is a perspective view of a detail.

The thread carrier bars 1—8 are arranged in the machine in a manner known per se. The thread carrier bars 3, 4 and 5, for instance, are controlled by a special change device of the thread carrier bars.

Upon a shaft 9, adapted to be swung by a pattern mechanism, arms 10, 11 and 12 are fixed which are connected together by a rod 13. In a manner known per se, a slide 15 is displaceably mounted upon the rod 13 by way of a fork 14.

The slide 15 also is displaceably mounted in a casing, not shown in the drawings. The slide 15 is provided with a conveyor dog 16 which is adapted to cooperate with the projections 17 of the thread carrier bars 3, 4 and 5.

In a bearing block 18, connected to the narrowing device mounted at each side of the machine, a shaft 19 is journaled upon which double-armed locking levers 20, 21 for the thread carrier bars 3, 4 and 5 are pivotally mounted. Fixed upon the end of each thread carrier bar 3, 4 and 5 is a locking block 22 which in a manner known per se cooperates with the corresponding locking lever 20, 21.

Mounted upon an arm provided at the bearing block 18 of the shaft 19 are springs 23 the other ends of which are connected to the corresponding lever arms 21.

Journaled in the bearing block 18 is another shaft 24 upon which cut away double-armed levers 25, 26 are arranged. The cut away ends of the lever arms 26 extend into the range of the corresponding lever arms 21 of the locking levers 20, 21. Arranged upon the shaft 24 is an arm 27 in which a bolt 28 is journaled. In the range of the locking lever arms 26 a lever 30 provided with a handle 29 is pivoted upon the bolt 28.

Fixed to the arms 10 and 11 are holders 31 each provided with a fork forming a guide.

Mounted in the holder 31 is a lifting rail 32 which is acted upon by springs 33. In accordance with the lever arms 26 the ends of the lever arms 25 also are cut away and extend into the range of the adjustable lifting rail 32. Fixed upon a shaft 34 are levers 35. One of these levers 35 is by means of a bolt 36 connected to one end of a link 37 the other end of which is connected to a cam lever 38 the roller 39 of which may be influenced by a cam 40. By means of a spring 41 the roller 39 is held into contact with the cam 40.

The operation of the device according to the invention is as follows:

If one of the pattern mechanisms not shown in the drawings is actuated, the shaft 9 and therewith the levers 10, 11 and 12 are swung. Hereby the rod 13 also is swung which by way of the fork 14 displaces the slide 15 the conveyor dog 16 of which adjusts itself to a projection 17 of one of the thread carrier bars 3, 4, 5. During the subsequent movement of the cam lever 38 which positively is started by the cam 40 the shaft 34 and therewith the lever 35 is swung by way of the link 37. The lifting rail 32 mounted in the holder 31 is hereby caused to rise. This

again causes lifting of the lever arm 25 adjusted upon the lifting rail 32 and lowering of the corresponding lever arm 26 which effects downward shiftment of the lever arm 21 of one of the locking levers 20, 21 situated in the range of this lever arm 26, whereby the other arm 20 of the locking lever releases the corresponding locking block 22 and therefore the corresponding thread carrier bar.

This operation is repeated at each change of the thread carrier in accordance with the sequence determined by the pattern mechanism.

As may be seen from Fig. 4, by means of the lever 30 all thread carrier bars 3, 4 and 5 to be changed may together be released by a single handle.

It is of no importance in which manner the change device for the thread carrier bars operates and how the change device is constructed.

Of particular importance, however, is the direct dependency of the locking device on the change device for the thread carrier bars without special pattern mechanisms being required.

What I claim is:

1. A flat knitting machine, comprising thread carrier bars, stops limiting the movement of said thread carrier bars, means for automatically locking all said thread carrier bars as soon as they reach their corresponding stops, means for releasing those of said thread carrier bars which continue to operate on movement in opposite direction, a change device for said thread carrier bars, including a pattern controlled shaft, pivotally mounted locking levers acting upon said thread carrier bars, springs pressing said locking levers to locking position, and a cam controlled mechanism for releasing said locking levers.

2. A flat knitting machine, comprising thread carrier bars, stops limiting the movement of said thread carrier bars, means for automatically locking all said thread carrier bars as soon as they reach their corresponding stops, means for releasing those of said thread carrier bars which continue to operate on movement in opposite direction, a change device for said thread carrier bars, including a pattern controlled shaft, a slide influenced by said pattern controlled shaft, a lifting rail loosely connected to said slide and actuated by said pattern controlled shaft, locking levers acting upon said thread carrier bars, springs pressing said locking levers to locking positions, and a cam controlled mechanism for releasing said locking levers.

3. A flat knitting machine, comprising thread carrier bars, stops limiting the movement of said thread carrier bars, means for automatically locking all said thread carrier bars as soon as they reach their corresponding stops, means for releasing those of said thread carrier bars which continue to operate on movement in opposite direction, a change device for said thread carrier bars, including a pattern controlled shaft, a cam controlled mechanism, a plurality of slides influenced by said pattern controlled shaft, a lifting rail loosely connected to said slides and actuated by said pattern controlled shaft and said cam controlled mechanism, locking levers acting

upon said thread carrier bars, springs pressing said locking levers to locking position, and said cam controlled mechanism adapted to release said locking levers.

5. A flat knitting machine, comprising thread carrier bars, stops limiting the movement of said thread carrier bars, means for automatically locking all said thread carrier bars as soon as they reach their corresponding stops, means for releasing those of said thread carrier bars which continue to operate on movement in opposite direction, a change device for said thread carrier bars, including a pattern controlled shaft, a slide influenced by said pattern controlled shaft, a lifting rail, double-armed levers actuated by said lifting rail, locking levers influenced by said double-armed levers and acting upon said thread carrier bars, springs pressing said locking levers to locking position, and a cam controlled mechanism for releasing said locking levers.

25 5. A flat knitting machine, comprising thread carrier bars, stops limiting the movement of said thread carrier bars, means for automatically locking all said thread carrier bars as soon as they reach their corresponding stops, means for releasing those of said thread carrier bars which continue to operate on movement in opposite direction, a change device for said thread carrier bars, including a pattern controlled shaft, a cam controlled mechanism, a plurality of slides influenced by said pattern controlled shaft, a lifting rail influenced by said pattern controlled shaft and said cam controlled mechanism, double-armed levers actuated by said lifting rail, locking levers influenced by said double-armed levers and acting upon said thread carrier bars, springs pressing said locking levers to locking position, and said cam controlled mechanism adapted to release said locking levers.

40 6. A flat knitting machine as set forth in claim 4 in which the number of said double-armed levers actuated by said lifting rail is equal to the number of thread carrier bars to be changed and in which said double-armed levers are cut away in such a manner, that on a change of the thread carrier bars occurring said lifting rail and said slide are commonly and positively adjusted to the corresponding double-armed lever and consequently to the locking lever.

50 7. A flat knitting machine as set forth in claim 5 in which the number of said double-armed levers actuated by said lifting rail is equal to the number of thread carrier bars to be changed and in which said double-armed levers are cut away in such a manner, that on a change of the thread carrier bars occurring said lifting rail and said slides are commonly and positively adjusted to the corresponding double-armed lever and consequently to the locking lever.

60 8. A flat knitting machine as set forth in claim 2, in which said cam mechanism comprises a shaft, a plurality of levers, fixed to said shaft and adapted to shift said lifting rail, a cam controlling said shaft, a lever actuated by said cam, and a link connected to said lever actuated by said cam and to one of said levers fixed to said shaft.

FRANZ CECKA.
